KNITTED LINING FOR RUBBER FOOTWEAR AND METHOD OF MAKING SAME

Application filed April 11, 1930. Serial No. 443,358.

The present invention relates to a knitted lining for rubber foot wear such as boots, and the like, and an improved method of producing such linings. The lining is particularly 5 adapted for use in the manufacture of rubber articles of foot wear that are formed, or built up, upon suitable lasts or trees having the shape of the completed articles.

The object of our invention is to provide an 10 improved lining of the above indicated character that is knitted in such a manner as to closely fit the last or tree upon which it is drawn preparatory to the formation of the rubber article thereon, by any suitable process. As a result of the close fit obtained between the last and our improved lining, the 15 lining itself becomes uniformly incorporated in the cured rubber of the finished article and so presents a smooth inside surface to the 20 foot of the wearer free of wrinkles. In addition, our lining is so made that the only seam therein becomes firmly embedded in the sole of the article of footwear the seam being formed at a place where it is not noticeable 25 to the wearer. The above and other advantageous features of our invention will herein-after more fully appear, reference being had to the accompanying drawing in which—

Fig. 1 is a plan view of a length of tubular 30 knitted material from which the lining is to be made.

Fig. 2 is a view in side elevation of a completed lining produced in accordance with our invention.

Fig. 2a is a fragmentary plan view of the 35 lining foot.

Fig. 3 is a view in side elevation of a boot last or tree on which the lining of Fig. 2 is to be drawn.

Fig. 4 shows the lining on the last.

Fig. 5 is a transverse sectional view of a completed boot incorporating the lining of Fig. 2 and showing the location of the toe 45 seam.

Fig. 6 is a side view of a lining similar to the lining shown in Fig. 2, but knitted in a different way.

Fig. 7 is a fragmentary view showing a 50 further modification of the lining of Fig. 2.

Like reference characters refer to like parts in the different figures.

In carrying out our invention, a length of material generally tubular in form, as shown in Fig. 1, is produced by a circular knitting machine with a portion 1 knitted in plain rib stitch. That portion of the material extending from the line *a*—*b* to the line *c*—*d* is then knitted with a portion 2 in plain rib stitch, while the adjacent portion 3 is knitted with a tuck stitch. In knitting the dissimilar portions 2 and 3, successive continuous courses are knitted partially in plain rib stitch and partially in tuck stitch, and as the portions 2 and 3 emerge from the machine, the fabric takes the form of an arc between the lines *a*—*b* and *c*—*d* with the portion 2 of larger radius because of the fact that the tuck stitch portion 3 contains a smaller number of 55 stitches than there are in the rib stitch portion 2 for a given number of courses, with each tuck stitch containing more yarn than a rib stitch. The gathering together of the 60 stitches of the portion 3 incident to tuck stitching results in shortening the line *b*—*d* 65 as compared to the line *a*—*c*. The gathering together of the stitches of the portion 3 incident to tuck stitching results in shortening the line *b*—*d* 70 as compared to the line *a*—*c*.

A further portion 4 of the fabric, extending from the line *c*—*d* to the end of the tube is then knitted with tuck stitch courses similar to the portion 3, and owing to the looseness of this portion 4, as compared to the portion 1 of plain rib stitch, the portion 4 is of considerably greater diameter than the portion 1. As a result of the above described 75 manner of knitting, a length of tubular fabric is produced with a straight portion of substantially uniform diameter, an arcuate portion of slightly increasing diameter and a relatively long and slightly tapered portion of still greater diameter.

The next step in carrying out our invention resides in bringing the edges of the portion 1 together and then cutting and sewing the edges, to provide a curved seam 5 which extends transversely to the axis of the tubular portion 1, as shown in Fig. 2a, the seam 5 lying in a plane at right angles to the plane in which the lining is curved when lying flat. By comparing the completed lining of Fig. 2 with the boot last of Fig. 3, it is apparent 90 95 100

that the lining closely approximates the actual form and proportions of the last so that when the lining is drawn on the last, as shown in Fig. 4, the lining will fit closely on the last 5 and present a smooth appearance. It will also be noted in Fig. 4 that the curved seam 5 is disposed along the bottom of the last just within and substantially parallel to the curved edge of the sole of the last. In drawing 10 the lining on the last, which is usually inverted for this purpose, no particular skill is required on the part of the operator, since the curved portion of the lining naturally points towards the toe of the last; consequently 15 the seam 5 always comes at the proper position with its stitches facing outward from the flat sole of the last.

After the lining has been drawn on the last, as shown in Fig. 4, the different parts of uncured rubber of which the boot is composed are built upon the lining covered last in a manner well known to those skilled in the art. These rubber boot parts include a sole which is placed flat on the covered last in engagement with the toe seam stitches 5 and is held in position by suitable leg and vamp pieces. The boot is then completed by subjecting the rubber parts to a vulcanizing process, with or without pressure as desired, 30 which results in the lining becoming an integral part of the completed article. In the completed boot shown in section in Fig. 5 it should be noted that the toe stitching 5 is firmly embedded in the sole 6 of the boot which is of considerably greater thickness 35 than the remainder of the boot. As a result of the close fit of the lining on the last and the embedding of the seam in the rubber sole, the lining presents a smooth unbroken inside surface throughout with no wrinkles or 40 seams noticeable to the foot of the wearer, and with no weak spots in the rubber due to irregularities in the thickness of the lining.

Another advantage of our lining resides in the fact that since the rib stitching of the toe, sole and heel portions of the lining is closer in texture than the instep and leg tuck stitching, these denser portions of the lining are better able to withstand the greater 45 wear to which they are subjected, as compared to the instep and leg portions. The wearing qualities of the lining in this respect can be further increased by introducing extra threads into those courses of the 50 lining between the lines *a*—*b* and *c*—*d* which are knitted partially in rib stitch and partially in tuck stitch, the extra threads being introduced either into the rib stitched portion 55 2, or into both portions 2 and 3. A portion 60 of a lining knitted in this manner is shown in Fig. 7, wherein the presence of the extra material is indicated in the rib knit portion 2*a* by the closer spacing of the wales.

Referring now to Fig. 6, there is shown a 65 modified form of lining which is adapted to

be made on an ordinary hosiery machine with a single stitch, whereas the lining shown in Fig. 2 is made on a cylinder and dial machine. In knitting this modified form of lining, a toe portion 7 is knitted with a relatively short stitch using small thread, after which a portion 8 is knitted with stitches of different length, the stitches 8*a* being shorter than the stitches 8*b* and the stitches 8*b* being knitted with larger thread as compared to the thread used for knitting the portions 7 and 8*a*. After this, a third portion 9 is knitted with stitches longer than the stitches of the other portions and with thread larger than the thread used in either the portions 7 70 and 8*a*. As a result of the above described manner of dissimilar stitching with different sizes of yarn, the intermediate portion 8 of the completed lining assumes a somewhat arcuate 75 form with one side longer than the other so that it will fit closely over the last shown in Fig. 3. The lining shown in Fig. 6 also provides a toe seam 10 disposed in the same manner as the toe seam 5 of the lining shown in Fig. 2 and this particular type of lining is 80 claimed in our copending divisional application Ser. No. 657,286, filed Feb. 17, 1933.

In the manufacture of rubber foot wear incorporating the linings described above, it has been found that the lining shown in Fig. 2 is particularly adapted for the manufacture 95 of molded rubber foot wear. In the manufacture of molded foot wear, it is customary to employ a last having walls of yieldable material, such as a combination of rubber and fabric, this material being of such stiffness as to maintain its shape against the forces involved in building the boot thereon. At the same time, a last of this type possesses sufficient elasticity to be expanded by fluid pressure to press the boot material against the rigid walls of an inclosing mold. We have found that a lining knitted in the manner shown in Fig. 2 possesses sufficient elasticity to expand uniformly with the last when the latter is inflated by pressure during the vulcanizing operation. Furthermore, the pressure exerted by the expanded last outwardly against the rigid walls of the inclosing mold serves to actually embed the longitudinal ribs of the lining in the rubber inclosing the lining, thereby giving a maximum degree of adhesion between the rubber and the lining in the completed boot. 105 110 115

On the other hand, the type of lining shown in Fig. 6 is particularly adapted for the manufacture of rubber foot wear on a rigid last, since the relatively tighter single stitching of the lining shown in Fig. 6 is adapted to fit more closely to the last and does not possess 120 the elasticity of the lining shown in Fig. 2. In the manufacture of rubber foot wear with a rigid last, it is customary to exhaust the air from the inside of the last during the vulcanizing operation which results in a difference 125 130 135

of pressure between the outside surface of the built up rubber boot parts surrounding the lining and the surface of the last. This difference in pressure results in the rubber and the lining being pressed against the unyielding surface of the last so that the last determines the form of the completed article. For this reason, the lining of Fig. 6, with its relatively slight elasticity and its absence of pronounced longitudinal ribs on the side in contact with the rubber is better suited for this mode of manufacture than the lining shown in Fig. 2, since this lining will adhere uniformly to the rubber without exhibiting any tendency for the stitching of the lining to affect the appearance of the outer rubber surface of the finished article of foot wear.

From the foregoing it is apparent that by our invention we have provided an improved knitted lining and a method of making the same by the practice of which it is possible to produce linings that are particularly adapted for use in connection with the manufacture of formed rubber foot wear, such as boots and overshoes, our linings, when incorporated in such articles, presenting a smooth unbroken surface which possesses considerable warmth for the foot of the wearer.

We claim:

1. The improvement in the manufacture of a lining for a formed rubber article which consists in knitting a length of tube with one portion in rib stitch, another portion partially in rib and partially in tuck stitch and a third portion in tuck stitch, the mixed rib and tuck stitched portion lying between the other portions to impart an arcuate form to the lining.

2. The improvement in the manufacture of a lining for a formed rubber article which consists in knitting a length of tube with one portion in rib stitch, another portion partially in rib and partially in tuck stitch and a third portion in tuck stitch, with the mixed rib and tuck stitched portion lying between the other portions and then closing the rib stitch portion by a curved seam extending transversely across the tube, with said seam lying in a plane at right angles to the plane in which the mixed stitch portion is curved.

3. A one-piece fabric lining for formed rubber articles of footwear knitted in tubular form with one side longer than the other, with the stitches at its end portions of different character, and with the stitches of an intermediate portion of mixed character corresponding to the stitches of said end portions.

4. A one-piece fabric lining for formed rubber articles of footwear knitted in tubular form to assume a shape closely approximating the shape of the last on which the article is formed, said lining comprising a foot portion knitted in rib stitch, a curved instep and heel portion knitted partially in

rib and partially in tuck stitch, with the rib stitching having the greater radius, and a leg portion knitted in tuck stitch.
